Attorney, Agent, or Firm—Darby & Darby

[57] **CLAIM**

The ornamental design for a combined rocking chair
and kneeler, as shown and described.

DESCRIPTION

FIG. 1 is a front perspective view of a combined rock-
ing chair and kneeler embodying my new design;
FIG. 2 is a rear perspective view from the other side of
the chair; and
FIG. 3 is a bottom perspective view of the chair.

Fig. 1.
